UNITED STATES PATENT OFFICE

132,811

DESIGN FOR A FLOOR MAINTENANCE MACHINE

William E. Holt, Oakland, Calif.

Application August 28, 1941, Serial No. 103,072

Term of patent 7 years

To all whom it may concern:

Be it known that I, William E. Holt, a citizen of the United States, residing at Oakland, in the county of Alameda and State of California, have invented a new, original, and ornamental Design for Floor Maintenance Machines, of which the following is a specification, reference being had to the accompanying drawings, forming part thereof.

Fig. 1 is a side elevational view of a floor maintenance machine, showing my new design;

Fig. 2 is a top plan view thereof with portions of the handle broken off for convenience of illustration;

Fig. 3 is a front elevational view thereof; and
Fig. 4 is a rear elevational view thereof.

I claim:

The ornamental design for a floor maintenance machine, as shown.

WILLIAM E. HOLT.
